[57] CLAIM

The ornamental design for a cover for a container,
substantially as shown.

DESCRIPTION

FIG. 1 is a top plan view of a cover for a container
showing my new design;

FIG. 2 is a side elevational view thereof;

FIG. 3 is an inverted side elevational view thereof;

FIG. 4 is a bottom plan view of the cover rotated 90°
from the showing in FIG. 1;

FIG. 5 is a side elevational view thereof;

FIG. 6 is an inverted side elevational view thereof;

FIG. 7 is an enlarged partial sectional view taken along
lines VII—VII of FIG. 1; and

FIG. 8 is an enlarged partial sectional view taken along
lines VIII—VIII of FIG. 1.
